UNITED STATES PATENT OFFICE.

CHARLES H. PARMELEE, OF SEATTLE, WASHINGTON.

WATER-TUBE BOILER.

1,269,849.

Specification of Letters Patent. Patented June 18, 1918.

Application filed November 21, 1916. Serial No. 132,713.

To all whom it may concern:

Be it known that I, CHARLES H. PARMELEE, citizen of the United States, residing at Seattle, in the county of King and State of Washington, have invented a certain new and useful Improvement in Water-Tube Boilers, of which the following is a specification.

My invention relates to improvements in water tube boilers, and the object of my invention is to provide a unitary structure which shall be adapted to be inclosed by suitable walls of masonry operatively to serve as a completed boiler, and which shall be further adapted to be operatively united side by side with another or any desired number of other like unitary structures each of which constitutes a unit, all of which units so united, may, when inclosed by walls, operate as a single larger boiler.

A further object of my invention is to provide a water tube boiler of such plan of construction that its parts readily may be assembled and disassociated thus to facilitate the operation of replacing any old part with a new like part, as, for instance, substituting a new tube for an old one, and to facilitate the operation of removing scaly deposits and dirt from the interior of the tubes of said boiler.

Another object of my invention is to provide a water tube boiler so constructed that its surfaces to be heated shall be so disposed with relation to a fire-box and passageways leading therefrom to a chimney, that said surfaces shall be most advantageously subjected to a contact with the heated gases generated in said fire-box.

I accomplish these objects by devices illustrated in the accompanying drawings wherein—

Figure 1 is a plan view of a boiler embodying my invention comprising two unitary structures disposed within a brick inclosure whose top wall is removed;

Fig. 2 is a view of the same in side elevation with its top wall in place but with its nearer side wall removed;

Fig. 3 is a complete view of the same in front elevation;

Fig. 4 is a view of the same in vertical cross-section on broken line 4, 4 of Fig. 2;

Fig. 5 is a view in front elevation of an unconnected one of said unitary structures, and Fig. 6 is a fragmentary view of details of the same.

Referring to the drawings, throughout which like reference numerals designate like parts, an inclosure is formed of oppositely disposed vertical side walls 7 and 8 and a vertical rear wall 9, preferably of brick, of which the walls 7 and 8 extend upwardly from a brick or concrete floor which is represented by a horizontal line 10, while the rear wall 9 extends upwardly from the top of the rear edge portion of a transversely disposed cast iron base member 11 which rests on the floor 10, as shown more clearly in Fig. 2.

Disposed on top of the rear wall 9 and on adjacent portions of the side walls 7 and 8 is a metal plate 12 from whose forward edge extends downwardly an integral flange 13 which serves as a deflector.

The plate 12 is provided with a circular opening through its central portion over which opening is fixed a chimney 14 through which smoke may escape from the interior of the inclosure.

Disposed on the top surfaces of the side walls 7 and 8 and on the top of the plate 12 is a top wall 15, preferably of fire-brick, which serves to cover the interior of the inclosure.

Disposed adjacent to and parallel with the upper portion of the front side of the base member 11 is an iron bar 16 which is of the shape of the letter T in cross-section, the opposite end portions of which bar 16 are embedded each in the adjacent one of the walls 7 and 8 respectively, and which bar 16 serves as a support for the rearward end portions of a plurality of grate-bars, like the grate-bars 17, whose forward end portions are disposed to be supported upon an off-set edge 18 of a transverse bar 19 whose opposite end portions are also embedded in the walls 7 and 8 adjacent to the vertical front edges of said walls 7 and 8 to be supported thereby.

Disposed within the space between the side walls 7 and 8 are two separable and like unitary structures each of which comprises a complete water tube boiler, but both of which are so joined one to the other that both of them when thus disposed within the same inclosure, may conjointly act operatively to serve as a single larger boiler; and upon tearing away the walls 7, 8 and 9 and removing associated fittings, said two unitary structures may be disconnected one from the other and each of them be inclosed in a sep-

arate inclosure to constitute two distinct and separate boilers.

Moreover, upon tearing away one of the side-walls 7 and 8 and removing associated side fittings, one or more like unitary structures could be joined to the adjacent one of said two unitary structures whereupon the rearward wall 9 could be lengthened, the top wall broadened and a new side wall made to inclose the three or more joined unitary structures to adapt them to act conjointly as a single larger boiler.

The two joined unitary structures within the inclosure formed by the walls 7, 8, 9 and 15 are both like the structure shown by a view in front elevation in Fig. 5, each embodying a horizontally disposed header, as headers 20 and 21 indicated by dotted lines in Fig. 4, which headers 20 and 21 are joined end to end by abutting flanges 22 and 23 respectively as more clearly shown by dotted lines in Fig. 4.

The headers 20 and 21, thus joined, are disposed to rest upon the base member 11, adjacent to the rearward wall 9, and connected to each of said headers 20 and 21, by means of unions, as unions 24 and unions 25 respectively, are three vertically disposed headers, as headers 26 and 27 as shown more clearly in Fig. 4.

The front side wall of each of the vertical headers 26 and 27 is provided with a plurality of screw-threaded holes within which are screwed the screw-threaded end portions 35 of boiler tubes, as boiler tubes 28 respectively, which boiler tubes 28 extend forward to project their other ends into and through holes in the rearward wall of corresponding vertical headers, like the vertical headers 40 30, disposed in the front end portion of the enclosure as indicated in Fig. 2.

The headers 30 are disposed to rest upon the top of the inwardly projecting portion of a door frame 31 which door frame 31 is disposed in a vertical metal front wall 32 which is disposed against the surface of the front ends of the walls 7 and 8 where it is secured by vertical bars 33; said door frame 31 opening into a fire box 34 above the grate-bars 17, and said door frame 31 being provided with two doors 35 and 36 shown in Fig. 3.

In the metal front wall 32, below the doors 35 and 36, are two other doors 37 and 38 which open into the ash-pit below the grate-bars 17.

The holes in the rearward wall of each of the vertical headers 30, through which the ends of the tubes 28 respectively, project, are countersunk on the interior side of said wall, and, opposite each of said holes, the frontward wall of each of said headers 30 is provided with a larger screw-threaded hole each of which holes except the top one is closed by a screw-threaded plug, as plugs

39, which larger screw-threaded hole is large enough to permit a boiler tube 28 to pass therethrough to dispose its rearward screw-threaded end in the wall of a corresponding header 26 or 27, and to permit the introduction of a tool for expanding the front end of a tube 28 to flare it to engage with the countersink inner surface of the rear wall of a header 30 as indicated by the fragmentary view shown in Fig. 6. 70 75

Extending through the front metal wall 32 into the uppermost screw-threaded hole in the front side of each of the vertical headers 30 is a nipple, like the nipple 40 shown in Fig. 2, the outer ends of which nipples 40 are connected by right and left hand screw-threaded couplings, like the coupling 41, with nipples provided in the rear side of two horizontally disposed joined headers 42 and 43 disposed parallel with and adjacent to the other side of the wall 32.

The front side of the headers 42 and 43 are provided with holes disposed opposite respective ones of the uppermost tubes 28 which holes are also closed by removable plugs 39.

Thus, by removing the plugs 39 a scraper may be inserted into the several tubes 28 to remove scale and dirt that may be accumulated therein.

Extending downwardly through the center of the top side of each of the horizontal headers 42 and 43 is a screw-threaded hole provided with a nipple and coupling, as couplings 44 and 45, respectively, which couplings 44 and 45 connect with the underside of the outwardly projecting end portions of two steam drums 46 and 47 which extend rearwardly within the inclosure with their end surfaces adjacent to the deflector 13. 100 105

Connecting with the interior of the steam drums 46 and 47 through the top side of the outwardly projecting end portions thereof by the means of T fittings 48, 49 and 50 and 110 couplings 51 and 52, is a delivery steam-pipe 53.

The outer end of the headers 42 and 43 are connected to T fittings 54 and 55, respectively, and interposed between the T fitting 49 and the T fitting 55 are pipe connections with which are associated gage cocks 56, a water gage 57 and a pressure gage 58, of well known form.

Extending downwardly from the T fittings 54 and 55 to T fittings 59 and 60 are pipes 61 and 62, respectively.

The T fittings 59 and 60 connect with the outer ends of pipes 63 and 64, respectively, which are embedded in the brick side walls 125 8 and 7, respectively, which outer ends project through the vertical bars 33; and said pipes 63 and 64 extend rearwardly to T fittings 65 and 66, indicated by dotted lines in Fig. 4, from which the T fittings 65 and 130

66 pipes 67 and 68, respectively, extend upwardly within said walls 8 and 7, respectively, to connect with T fittings 69 and 70, respectively, as indicated by dotted lines in said Fig. 4.

Disposed to extend transversely between the T fittings 69 and 70 above the tubes 28, is a pipe connection 71 which includes T fittings 72 and 73, which T fittings 72 and 73, respectively, connect with nipples 74 and 75 which are screwed into the underside of the inner end portions of the steam drums 46 and 47, respectively.

The rearward terminals of the T fittings 65 and 66 are connected to pipes, like the pipe 76 shown in Fig. 2, which pipes 76 connect respectively with the outer ends of the horizontal headers 20 and 21 by the means of T fittings, like the T fitting 77 shown in Fig. 2, which T fittings are embedded in the walls 8 and 7, respectively, the outer terminal of the T fitting 77 being connected with a water feed pipe 78, while the outer terminal of the corresponding T fitting that is connected with the end of the header 21, is closed by a removable plug 79, as shown more clearly in Fig. 4; thus by disconnecting the feed pipe 78 and removing the plug 79, the interior of the headers 20 and 21 may be cleaned with facility.

Disposed upon the top of the base member 11 is a block 80 and a deflector 81, of refractory material, as of fire brick, and disposed on the top sides of the bottom row of tubes 28 is a deflector 82, of refractory material, which extends from the front end of the inclosure to a point spaced from the deflector 81, thus to cause all products of combustion and heated gases to pass in the direction of the arrow (shown in Fig. 2) from the fire-box 34 through the space between the rearward end of the deflector 82 and the front side of the deflector 81.

Disposed upon the top of the tubes 28 is a deflector 83 which extends from the rearward vertical wall 9 to a point spaced from the front metal wall 32 whereby heated gases must traverse throughout the length of the space between the deflectors 82 and 83 to flow upwardly in the direction of the arrow to impinge against the frontward portion of the steam drums 46 and 47, thence to flow rearwardly to pass beneath the deflector 13, thence upwardly through the chimney 14, as indicated by the longer curved arrow in Fig. 2.

The outer ends of the T fittings 69 and 70 are provided with removable plugs 84 and 85, respectively, which may be removed to clean the interior of the pipe connection 71 and elbows 72 and 73.

The T fittings 59 and 60 are also provided with plugs, as plugs 86 and 87, which plugs may be removed to clean the interior of the pipes like the pipe 68.

The feed water pipe 78 may be extended to a convenient source of water and the delivery steam pipe 53 may be extended to a desired point of delivery.

As thus constructed the weight of the steam drums 46 and 47 is supported by the pipe connection 71 and the headers 12 and 43 coating with the outwardly projecting end of the pipes, like the pipe 63, to which pipes the T fittings 59 and 60 are connected, and the weight of the tubes 26, 27 and 30 are supported by the door frame 31 and the base member 11, in an obvious manner, the door frame 31 being supported by the transverse bar 19.

The operation of my invention as embodied in the boiler illustrated by the drawings may be described as follows: Water is admitted through the feed pipe 78 to fill the tubes 28, the associated headers, and pipe connections, and to rise therefrom into the steam drums 46 and 47 to the level indicated by broken lines in Fig. 4, thereupon a fire is made in the fire-box 34 with the result that heated gases will flow therefrom through the space between the deflectors 81 and 82, thence to pass forwardly through the space between the deflectors 82 and 83, thence to pass upwardly through the space between the front end of the deflector 83 and the front metal wall 32, thence to flow rearwardly within the space surrounding the steam drums 46 and 47 to be deflected downwardly by the deflector 13, thence to flow upwardly through the chimney 14, whereby the water tubes 28 and the steam drums 46 and 47 will most advantageously absorb the heat of such gases to produce the most economical result.

Manifestly, if it be desired, one or more unitary structures embodying my invention may be associated with a metal inclosure lined with suitable refractory material thus to form a single portable boiler and changes may be made in the forms, dimensions and arrangement of parts of my invention without departing from the spirit thereof.

What I claim is:

1. In a water tube boiler, the combination of a plurality of upper longitudinal steam drums, a plurality of transverse horizontal headers detachably joined end to end, each connected to and arranged below one of the drums at the forward end thereof, rear and front substantially vertical headers arranged below said drums, a plurality of substantially horizontal water tubes connecting said vertical headers, pipe connections between the front vertical headers and the transverse horizontal headers, and pipe connections extending from the rear ends of said steam drums and from the transverse horizontal headers to the rear vertical headers.

2. In a water tube boiler, the combination of a plurality of upper longitudinal steam drums, a plurality of transverse horizontal headers detachably joined end to end, 5 each connected to and arranged below one of the drums at the forward end thereof; rear and front substantially vertical headers arranged below said drums, a plurality of substantially horizontal water tubes connecting said vertical headers, pipe connections between the front vertical headers and the transverse horizontal headers, rear transverse horizontal headers detachably joined end to end and connected to and arranged 10 beneath the rear vertical headers, and pipe connections extending from said first named transverse horizontal headers and from the rear ends of said steam drums to the second named transverse horizontal headers.
- 15 3. In a water tube boiler having front and rear substantially vertical headers with substantially horizontal water tubes connecting the same, a front horizontal transverse header connected to the front substantially vertical header, a rear horizontal transverse header connected to the rear substantially vertical header and pipe connections between the front and rear transverse headers, said front and rear transverse headers having their ends formed for ready connection with additional similar headers whereby the boiler may be enlarged.
- 20 4. A water tube boiler including front and rear substantially vertical headers connected by substantially horizontal longitudinal water tubes, a longitudinal steam drum 50 above said water tubes, a transverse front horizontal header connected to the forward end of said steam drum and to the top of said front substantially vertical header, a transverse rear horizontal header connected 55 to the bottom of the rear substantially vertical header, and pipe connections between the rear end of the steam drum and the front and rear transverse headers, said transverse headers having their ends formed 60 for ready connection with additional similar headers whereby the boiler may be enlarged.
- 25 5. A water tube boiler including front and rear substantially vertical headers connected by substantially horizontal longitudinal water tubes, a longitudinal steam drum 50 above said water tubes, a transverse front horizontal header connected to the forward end of said steam drum and to the top of said front substantially vertical header, a transverse rear horizontal header connected 55 to the bottom of the rear substantially vertical header, and pipe connections between the rear end of the steam drum and the front and rear transverse headers, said transverse headers having their ends formed 60 for ready connection with additional similar headers whereby the boiler may be enlarged.
- 30 In witness whereof, I hereunto subscribe my name this 10th day of November, A. D. 65 1916.
- 35 CHARLES H. PARMELEE.
- Witnesses:
